DISPENSER

Cesare Barbieri, New York, N. Y., assignee to
Vortex Cup Company, Chicago, Ill., a corpora-
tion of Delaware

Application June 5, 1933, Serial No. 674,353

13 Claims. (Cl. 312—44)

My invention relates to dispensing devices adapted particularly for dispensing flat bottom frusto-conical and flanged paper drinking cups one by one from a stack of internested cups.

5. An important object of the invention is to provide improved construction and operation of escapement members which will insure positive separation and freeing of the lowermost cup from the bottom of the stack as soon as the escapement members have been withdrawn from below the flange of the lowermost cup.

10.

15 A further object is to provide escapement members operable, while other escapement members are being withdrawn from the lowermost cup, to project below the flange of the next lowermost cup to assume support of the stack above the lowermost cup and to then exert wedging and rotational efforts against the lowermost cup to positively separate such cup from the bottom 20 of the stack after it has been released from the escapement members.

Another object is to provide subsequently operable escapement members having wedged ends of arcuate extent and adapted to be moved along the upper edge of the lowermost cup to wedge it away from the next cup and to exert frictional drag on the cup tending to cause rotation thereof for easier separation thereof from the next cup so that after release of the lowermost cup from initial escapement members it will be entirely free from the next cup so that it may drop from the dispensing tube without delay.

My invention also involves other features of construction, arrangement and operation, all of the features of the invention being incorporated in the structure disclosed on the accompanying drawings, in which drawings

Figure 1 is an elevational view of a dispenser; Figure 2 is an enlarged elevation of the dispenser body structure with the enclosing shell and stack-enclosing dome removed.

stack-enclosing dome removed;

Figure 3 is a plan view of the body structure;

Figure 4 is a section on plane IV—IV of Figure 2 showing the dispensing mechanism in normal stack supporting position;

Figure 5 is a view similar to Figure 4 showing escapement members in cup discharging position; the entire figure having been rotated clockwise 50 to align the major portion of the mechanism with Figure 4 for the purpose of clarity.

Figure 6 is a section on plane VI-VI of Figure 2;

Figure 7 is a section on plane VII—VII of
55. Figure 4;

Figure 8 is a section on plane VIII—VIII of Figure 4;

Figure 9 is an enlarged section on plane IX-IX of Figure 4;

Figure 10 is an enlarged section on plane X-X of Figure 4; and

Figure 11 is an enlarged section on plane XI—XI of Figure 5.

The dispenser body comprises a tubular cylindrical metal frame 1 having secured thereto intermediate its ends an annular flange or ring 2. Spaced a distance below this upper ring 2 is a similar ring 3 surrounding the body 1 and being rotatable thereon, it being provided with a laterally extending arm 4 terminating in a vertical finger plate 5 by means of which the ring may be readily rotated. The ring 3 may be strengthened and supported by a bearing hub 6 below the ring and surrounding and bearing on the body member 1. The hub is vertically supported by 20 a bearing collar 7 secured to the member 1. This collar may be detachably secured as by means of screws 8.

Between the two rings the body 4 has the diametrically opposite circumferentially extending slots or open spaces 9 and 10 through which two sets of escapement members may project for control of the passage of cups through the body 4. These escapement members are supported on the rotatable lower ring 3, and I have shown two diametrically opposite escapement members E and E' and two other diametrically opposite escapement members D and D'. The controlling members are hinged or pivoted on the ring 3 and are provided with cam slots into which pins extend from the stationary upper ring 2 so that upon rotation of the ring 3 the controlling members will be operated.

Describing first the construction and operation of the escapement members E and E', each member is, as shown, in the form of a flat arcuate plate 11 resting on the ring 3 and having at its ends the upwardly extending spacing and guide lugs 12 and 12' engaging at their upper ends against the ring 2. Each plate 11 has the body part a and the tail end b, the tail end receiving a pivot pin 13 extending upwardly from the ring 3, these pivot pins 13 being adjacent to the solid sections of the body 11 between the open spaces 9 and 10 therein while the bodies a of the plates are at such open spaces for projection therethrough. The inner edges of the plate bodies a are bevelled downwardly to provide ledges C for engaging below the flanges of the cups to be dispensed. The cups 14 are shown of frusto-

conical shape with flat bottoms and with rounded or curled flanges 15 at their upper edges. The external diameter of these flanges is slightly less than the internal diameter of the dispensing body 1 so that the cups may readily pass therethrough.

The other escapement members D and D' comprise each a body plate 16 of arcuate form having the outer depending flange or lug 17 and the inner wedge forming lug 18, the lugs bearing on the ring 3 and holding the top of the plate against the upper ring 2 so that these members will be guided between the rings. The tail end 16' of the plate 16 is pivoted by a pin 19 to one end of a link 20 which at its other end is pivoted to a pin 21 extending upwardly from the ring 3. The pins 21 are adjacent to the pins 13 which pivot the escapement members E and E', the links being above the tail ends of the escapement members E and E' and below the tail ends of the escapement members D and D' as clearly shown in Figures 4, 5 and 11.

As shown, the escapement members E and E' extend circumferentially from their pivot points and along the ring 3 in clockwise direction while the escapement members D and D' extend in counter-clockwise direction.

As best shown in Figure 8, the inner flange 18 on each of the plates 16 is cut away and formed to provide a wedge surface 22 with the point of the wedge at the outer end of the plate, the wedge flange being transversely bevelled on its inner side as indicated in Figure 9. These wedge flanges are adapted for projection through the open spaces 9 and 10 in the body 1 for cooperation with the cups.

The plate 11 of each of the escapement members E and E' has an outer longitudinally extending slot 23, an inner longitudinally extending slot 24 and an intermediate diagonally extending slot 25. The plate 16 of each of the escapement members D and D' has two slots, each comprising a longitudinally extending section 26 and an outer diagonally extending section 27 extending therefrom. Depending from the upper ring 2 are the pins 28 and 28' for engaging in the slots of the escapement members E and E' respectively. A pair of pins 29 extends from the ring 2 for engagement in the respective slots in the escapement member D while a pair of pins 29' extends from the ring for engagement in the respective slots of the escapement member D'.

In the normal positions of the parts, as shown in Figure 4, the pins 28 and 28' are at the inner ends of the slot sections 23 and the pins 29 and 29' are at the outer ends of the slot sections 27. The escapement members D and D' are in positions in which their wedge ends are withdrawn from the interior of the tube 1 but the escapement members E and E' are in position to project their supporting ledges C into the tube 1 for engagement below the flange of the lowermost cup of the stack of cups supported in the containing member 1. A spring 30 extending between a pin 31 on the collar 7 and a pin 32 on the ring 3 tends to hold the ring 3 in normal position with the stop lug 33 thereon against the stop shoulder 34 on the collar 7.

By means of the arm 4 the ring 3 is rotated in counterclockwise direction against the pull of the spring 30 and until the stop lug 33 abuts the stop shoulder 35 on the ring 7. During the forepart of this rotational movement of the ring the longitudinally extending slots 23 of the escapement members E and E' pass along the pins 28 and there will be no radial movement of these

escapement members. Also during the forepart of the rotational movement of the ring, the diagonal slot sections 27 in the escapement members D and D' pass along the pins 29 and 29' respectively so that these escapement members will be 5 swung to project the points of the wedge flanges 18 into position between the flanges of the lowermost cup and the next cup. This primary movement of the escapement members D and D' is a combined longitudinal and radial movement so 10 that the wedge flanges are brought a sufficient distance between the cup flanges for the delivery members to engage below the flange of the next lowermost cup for support of the stack above the 15 lowermost cup.

During the final rotational movement of the ring 3 the diagonal slot sections 25 of the escapement members E and E' engage along the pins 28 and these escapement members are moved outwardly to withdraw their supporting ledges C 20 from underneath the lowermost cup so as to free this cup from the escapement members. During the final rotational movement of the ring 2 the longitudinal slot sections 26 of the escapement members D and D' pass along the pins 29 and 29' and the wedge surfaces are moved circumferentially along the top of the flange of the lowermost cup and during such circumferential movement these escapement members are moved radially inwardly, this radial inward movement 30 taking place because the longitudinally extending slot sections 26 are also slightly diagonal as clearly shown in Figure 4.

As the circumferentially extending wedge surface is also of bevelled or wedge-shaped transversely, the wedge flanges will wedge in circumferentially and radially between the flanges of the two lowermost cups and the lowermost cup will be positively forced away and entirely freed from the next cup. As cups in a stack are 40: 35: 45: 50: 55: 60: 65: 70: 75: 80: 85: 90: 95: 100: 105: 110: 115: 120: 125: 130: 135: 140: 145: 150: 155: 160: 165: 170: 175: 180: 185: 190: 195: 200: 205: 210: 215: 220: 225: 230: 235: 240: 245: 250: 255: 260: 265: 270: 275: 280: 285: 290: 295: 300: 305: 310: 315: 320: 325: 330: 335: 340: 345: 350: 355: 360: 365: 370: 375: 380: 385: 390: 395: 400: 405: 410: 415: 420: bers E and E' are projected through the spaces, as indicated at 36 in Figure 7. This arrangement will increase the abutting surface of the cup flange with the tube 4 to hold the cup against distortion while the wedge mechanism is operating.

An enclosure shell 37 may be provided for enclosing the operating structure, and this shell will be provided with a slot 38 through which the arm 4 of the ring 3 extends so that the finger plate 5 will be at the outside of the shell for controlling the rotation of the ring 3. A ferrule or base 39 may be provided above the enclosure 37 for mounting of the stack container or closure 40 which may be of glass.

I have shown and described a practical and efficient embodiment of the various features of my invention, but I do not desire to be limited to the exact construction, arrangement and operation shown and described as changes and modifications may be made without departing from the scope and spirit of the invention.

I claim as my invention:

1. In a dispenser for flanged cups, a frame forming a vertical passageway for delivery of cups from a stack extending into the passageway, escapement members surrounding said passageway, some of said members having ledges for engaging below the flange of the lowermost cup in a stack and others of said members having ledges for engaging below the flange of the next cup of the stack, means adapting said members for bodily oscillation circumferentially relative to said passageway, means adapting said members for radial movement relative to said passageway, and guide means controlling the relative movement of said members for alternate projection into said passageway of said lower cup engaging and next cup engaging ledges whereby to control the one-by-one escapement of cups from the stack.

2. In a dispenser for flanged cups, a frame forming a vertical cylindrical passageway for delivery of cups from a stack, escapement members surrounding said passageway, means for imparting bodily oscillation to said members in a direction circumferentially relative to said passageway, guide means defining radial movements for said members during bodily oscillation thereof, said movements cooperating to cause resultant movements of said members into engagement with the flanges of the cups of a stack for one-by-one escape of cups from the stack.

3. In a dispenser for flanged cups, the combination of a frame providing a vertical cylindrical passageway for delivery of cups from a stack, an oscillatable support on said frame around said passageway, escapement members mounted on said support to move bodily therewith in direction circumferentially relative to said passageway, said members being adapted for radial movement on said support, means guiding the radial movement of said members during bodily circumferential movement thereof, and escapement ledges on said members for projection into said passageway for escapement engagement with the cups.

4. In a dispensing device for flanged cups, a frame forming a vertical cylindrical passageway for delivery of cups from a stack, a first set of escapement members cooperable with the bottom of the flange of the lowermost cup in a stack, a second set of escapement members cooperable with the lower side of the flange of the next cup, means for imparting bodily circumferential move-

ment and radial movement to said members relative to said passageway, and wedge surfaces on the members of said second set, said wedge surfaces extending circumferentially for engagement throughout their extent with the upper edge of the lowermost cup to impart wedging and rotational movement to said cup for separation thereof from the stack after release of the cup from the escapement members of the first set.

5. In a dispenser for flanged cups, the combination of a frame forming a vertical cylindrical passageway for delivery of cups from a stack, lower escapement members for engagement below the flange of the lowermost cup of a stack, upper escapement members for engagement below the flange of the next cup in the stack, actuating means for imparting bodily circumferential movement of said escapement members relative to said passageway, and guide means effective during such bodily movement of the members for causing sequential radial movement of the members for the one-by-one escapement of cups from a stack.

6. In a cup dispenser of the class described, the combination of lower and upper escapement members cooperable respectively with the flanges of the lowermost and next cups of a stack, actuating means for imparting bodily oscillation to said members in a direction circumferentially relative to cups engaged thereby, a wedge surface on the underside of each of said upper escapement members extending along an arc to fit the top of the flange of the lowermost cup, guide means associated with the lower escapement members operable during oscillation of said members to effect transverse movement of said members into and out of position below the lowermost cup flange, and guide means associated with said upper escapement members operable during oscillation of said members to first effect transverse movement thereof for application of the wedge surfaces against the upper edge of the lowermost cup and then lengthwise movement of said surfaces in engagement with the cup edge to impart rotary movement to the cup.

7. In a dispenser of the class described, an escapement mechanism for delivering flanged cups singly from a stack, said mechanism including a member adapted to bodily move circumferentially relatively to the cups between and in engagement with the flanges of adjacent cups, said member having an inner edge substantially paralleling the cup flanges and a wedge surface to exert downward pressure against the lower cup during circumferential movement thereof for effecting separation of the cups.

8. In a dispenser for nested cups made of paper or the like and each having a flanged or beaded open end, a tubular member in which the stack is adapted to extend, movable means in said member for engaging the flanged end of the lowermost cup in the stack to support the stack of cups, additional means in said member movable between the flanged ends of the two lowermost cups, as said first movable means is moved out of engagement with the lowermost cup, for forcibly ejecting the lowermost cup, said latter means including a wedge-like element bodily movable circumferentially relatively to the cups and progressively between the flanged ends of said lowermost cups whereby the lowermost cup is cammed off the stack.

9. In a dispenser for nested cups made of paper or the like and each having a flanged or beaded open end, a tubular member in which the stack is adapted to extend, movable means in

said member for engaging the flanged end of the lowermost cup in the stack to support the stack of cups, additional and separate means in said member movable between the flanged ends of the two lowermost cups, as said first movable means is moved out of engagement with the lowermost cup for forcibly ejecting the lowermost cup, said latter means including a wedge-like element movable circumferentially and progressively between the flanged ends of said lowermost cups whereby the lowermost cup is cammed off the stack, and common actuating mechanism for said two means for retracting the former means while inwardly projecting the latter means and vice versa.

10. In a dispenser for nested cups made of paper or the like and each having a flanged or beaded open end, a tubular member in which the stack is adapted to extend, movable means in said member for engaging the flanged end of the lowermost cup in the stack to support the stack of cups, additional and separately mounted means in said member movable between the flanged ends of the two lowermost cups as said first movable means is moved out of engagement with the lowermost cup, for forcibly ejecting the lowermost cup, said latter means including a wedge-like element movable circumferentially and progressively between the flanged ends of said lowermost cups whereby the lowermost cup is cammed off the stack, said wedge element being formed flat on its upper side to support the stack while its un-

derside is progressively tapered to press and twist the lowermost cup off the stack of cups.

11. In a dispenser of the character described, an escapement mechanism for delivering peripherally flanged cups from a stack, said mechanism including a member shaped to extend between the flanges of adjacent cups of the stack and cause a separation of the lower cup from the upper when the member is moved, said member being bodily movable circumferentially relatively to the cups of said stack, and actuating means for said member.

12. In a dispenser of the character described, an escapement member shaped to cause delivery of a cup from a stack when the member is moved, said escapement member being bodily movable circumferentially relatively to the cups of the stack, actuating means for said member, and guiding means for guiding said member radially into and out of engagement with the cups.

13. In a dispenser of the character described, escapement mechanism for dispensing cups from a stack, said mechanism including a member normally disposed for engagement with the lowermost cup of the stack beneath a portion of said lowermost cup, a second member separate from the first said member normally disposed out of engagement with the cups, said second member being shaped to cam off the lowermost cup of the stack when moved into engagement therewith, and actuating means for sequentially actuating said members to dispense a cup.

CESARE BARBIERI.
